FIG 3

UNITED STATES PATENT OFFICE.

BURNHAM C. STICKNEY, OF ELIZABETH, NEW JERSEY, ASSIGNOR TO UNDERWOOD TYPEWRITER COMPANY, OF NEW YORK, N. Y., A CORPORATION OF DELAWARE.

TYPE-WRITING MACHINE.

1,100,269.

Specification of Letters Patent.

Patented June 16, 1914.

Original application filed April 17, 1903, Serial No. 153,024. Renewed March 3, 1909, Serial No. 481,022. Divided and this application filed January 24, 1912. Serial No. 673,130.

To all whom it may concern:

Be it known that I, BURNHAM C. STICKNEY, a citizen of the United States, residing in Elizabeth, in the county of Union and 5 State of New Jersey, have invented certain new and useful Improvements in Type-Writing Machines, of which the following is a specification.

This invention relates to so-called visible 10 writing machines in which the line of writing is always in view and especially to those of the front strike class.

This application, which is a division of 15 my application No. 481,022, filed March 3, 1909, which is a renewal of my application No. 153,024, filed April 17, 1903, relates to escapement mechanism for the paper carriage, which is movable in letter-feeding 20 direction, being for this purpose mounted upon a frame. Said frame is hinged to the main framework of the machine so as to permit the frame and carriage to swing or 25 tilt upwardly, thereby giving access to the under side of the platen and carriage, as well as to that portion of the typewriter mechanism which lies below the carriage, for purposes of inspection, cleaning, repair, manipulation, etc.

The typewriter keys control the feeding 30 movement of the carriage, and suitable provision is made for connecting the keys, which are mounted on the main frame of the machine, to control the carriage, which is movable up and off from the machine. In 35 the preferred form of the invention, the carriage-driving spring barrel is mounted on said hinged frame to swing up with the carriage; and the letter-feeding dogs, which engage the carriage rack to restrain the 40 same, are also mounted on said swinging frame; provision being made whereby the keys may operate said dogs when the frame and carriage are swung or folded down into closed relation with the main framework of 45 the machine.

In my said application No. 481,022, filed 50 March 3, 1909, I claim the arrangement of ribbon spools on said hinged frame for the purpose of bringing the spools up into accessible position when desired, and of bringing them to a position down out of the way

in the rear portion of the machine below the carriage, when the carriage and frame are folded down. In my application No. 475,930, filed February 3, 1909, (a division 55 of No. 153,024) I claim broadly the platen-shifting mechanism and the carriage disclosed herein; and in my application No. 729,273, filed November 4, 1912, (a division of No. 153,024) I claim the case-shifting 60 mechanism for the paper-carriage.

My present application is directed broadly to the feature of the tension mechanism for the carriage as being mounted to move bodily with said carriage into and out of coöperative 65 relation with the type-bars, and also of the escapement mechanism as being similarly mounted and movable.

Other objects and advantages will hereinafter appear; and my invention further 70 consists in certain combinations of devices, features of construction, and arrangements of parts, which will be hereinafter fully described and particularly pointed out in the concluding claims.

In the drawings forming part of this specification, Figure 1 is a longitudinal sectional elevation of a front strike writing machine embodying my improvements, one type action being shown in printing position, and the carriage being shown in full lines in normal position, and in dotted lines when tilted up to render the ribbon spools accessible to the operator; the position of the platen when capitals are being written 85 being also indicated by dotted lines below the full-line position. Fig. 2 is a plan; and Fig. 3 is a sectional front view of the machine.

The framework of the machine comprises 90 side walls 1, whose lower portions may be connected to form a base, and a top plate 2 supported upon said walls; a portion of the top plate being depressed, as at 3, to make room for the paper carriage and its 95 supports. Forwardly extending type bars 4 are pivoted at their rear ends upon a curved fulcrum-rod 5 mounted in a segment 6, and strike rearwardly against a cylindrical or other platen 7. The segment is radially slotted at 8 to receive the type-bar hubs; and preferably both the segment and

the fulcrum-wire incline upwardly and rearwardly, so that the types may strike upon the front side of the platen at a point a little above the horizontal plane of the platen axis. Each type-bar is provided with a lower-case type 9 and an upper-case type 10, the former being uppermost when the type bar is in printing position, although this relation may be reversed 5 within the scope of my improvements, and the type-bars may be otherwise mounted. The type bars may be operated by any suitable means, as for instance pull-links 11 and forwardly-extending levers 12 10 connected to the links and bearing at their forward ends keys 13; said key-levers being fulcrumed at their rear ends upon a transverse bar 14, and being provided with returning springs 15.

20 The platen 7 may be mounted by means of an axle 16 upon a carriage which may be of any suitable construction, and is illustrated as comprising side bars 17, united at their rear ends by a longitudinal bar 18, 25 said side bars extending rearwardly from the platen axle; and arms 19 extending downwardly and rearwardly from the platen axle, and connected at their lower ends by a longitudinal carriage-guiding bar 20. Upon a forwardly protruding boss 21 30 about midway of said bar 20 is mounted a carriage roll 22, which runs upon a horizontal rail 23, provided upon its rear side with a depending flange 24. Secured by 35 screws 25 upon the rear side of this flange are upstanding arms 26, which support a cylindrical rail 27. The carriage-bar 20 is bored longitudinally to slide along upon this rail 27, and is also recessed upon its 40 under side at 28 to pass the arms 26. A finger 29, secured by the carriage-roll screw 30, hooks under the front edge of the rail 23, thereby coöperating with the bar 20 to hold the carriage upon the rails. A feeding-in roller 31 may be mounted in rear 45 of the platen upon links 32 rising from ears 33 on the carriage-bar 20; and said links may be provided with rearwardly-extending lugs 34 for receiving legs 35 of 50 a paper-shelf 36. From the front side of the bar 20 may project forwardly and upwardly extending arms 37, upon whose forward ends may be hinged at 38 a bail consisting of a pair of upwardly and forwardly 55 extending arms 39 and a platen-scale 40 fixed upon the forward ends of said arms and provided with an apron 41 upon its rear side contiguous to the platen; the upper edge of said scale being below the printing 60 line upon the platen. One or more pressure rollers 42 may be mounted upon an axle 43 mounted at its ends in said arms 39 about midway of their length. Any suitable springs may be provided for the 65 front and rear pressure rollers. So far as

my present improvements are concerned, the carriage, paper-feeding means and carriage-supporting and guiding bars or rails may be of any other desired construction.

The flanged rail 23, 24 forms part of a 7 movable frame, whereby the paper carriage is enabled not only to run in letter-space direction, but to move also in a direction transverse thereto. This frame comprises, in addition to said rail (which need not be flanged in all cases) rearwardly extending arms 44, which are united at their forward ends by said rail, and a rock-shaft 45, which unites the rear ends of said arms, said rock-shaft being horizontally mounted or hinged upon pintles 46; working in ears 47 projecting forwardly from the front portion of the rear part of the top plate 2. The carriage and its supporting frame may be swung together up about said hinges and tilted rearwardly to the dotted line position at Fig. 1, so as to expose the underside of the carriage. Said supporting frame may, however, be otherwise formed and otherwise movably supported within the scope of my 90 improvements.

In rear of the type bars and below the platen are mounted upon an axle 48 a pair of ribbon spools 49, 50, said axle being horizontal, and said spools being arranged on 95 edge and side by side. The axle 48, which extends transversely of the machine, that is, from side to side thereof, or from left to right, is mounted in and transfixes the lower end of a forwardly and downwardly extending arm 51, preferably cast integral with the rock-shaft 45, and having an elongated boss 52 for suitably supporting the axle 48. It will be perceived that when in normal position the ribbon spools are inaccessible to the operator, but that when the hinged frame is swung up to the dotted line position at Fig. 1, said spools are brought to an accessible position, for convenience in examining or adjusting or attaching the ribbon, or of detaching or replacing the spools, etc. The depressed portion 3 of the top plate is preferably cleft, as at 53, to make room for the spools, which in normal position dip below said depressed 110 portion.

For rotating the spools, I preferably use a pair of pawls 54, 55, operated at every type stroke, and adapted to engage a pair of ratchet wheels 56, associated with the ribbon 120 spools. The latter may be slipped off and onto the axle 48, being retained by thumb-nuts 57; and each ratchet wheel may be connected to its spool by a collar or other device 58, so that one spool with its ratchet 125 may turn upon the axle independently of the other spool and its ratchet. If desired, the member 58 may be splined to the spool, as at 58^a, so as to permit the latter to be slipped off.

From one spool the ribbon 59 is led forwardly and upwardly, as at 59^a, then across the printing point at the front side of the platen, as at 59^b, and then back to the other spool, as at 59^c. At the front side of the platen are provided ribbon-guiding arms 60 and 61, formed at their upper ends with reversely inclined tips 62, 63, the angle of each tip being about 45 degrees, for properly conducting the ribbon across the printing point or field between its ascending and descending portions. Said arms 60 and 61 form part of a ribbon vibrator, being connected at their lower ends by a cross-arm 64, whereby they are supported upon a bent arm 65, which extends backwardly beneath the rail 23 and at its rear end is pivoted by means of a rock-shaft 66 upon bearing-arms 67 and 68, both of the latter projecting forwardly from the rock-shaft 45 of the carriage-supporting hinged frame, and arm 67 overlying the spool-carrying arm 51. By this vibrator, the ribbon may be lifted to cover the printing point at each impression, as at Fig. 1, and depressed to uncover the same; and since the vibrator is mounted upon the hinged frame, it is carried up with the latter when tilted to the dotted-line position at Fig. 1, thus facilitating the reeving of the ribbon from the spools over the guiding arms 62 and 63. Said ribbon-vibrator is operatively connected to carriage-feeding mechanism also mounted upon the hinged carriage-supporting frame and coöperating with a rack 69 on the carriage; said feeding mechanism comprising a detent dog 70 and a feeding dog 71, the latter being normally in engagement with the rack. These dogs are mounted upon a rocker or rock-shaft 72, mounted upon ears 73 and 74 upon the rock-shaft 45; and said rocker 72 is provided with an operating arm 75 which curves downwardly and rearwardly beneath the rock-shaft 45, in position to be operated by a finger 76 projecting forwardly from the upper end of an upstanding rocker-arm 77, fixed upon a rock-shaft 78 mounted transversely in the base of the machine. Said rock-shaft 78 carries near its ends forwardly directed arms 79, from which is suspended, by means of rods 80, a universal bar 81, extending transversely beneath all of the type-operating key-levers 12; so as to be operated at each type stroke. The universal bar and rocker 78 may be returned to normal position by a spring 82; and a returning-spring 83 for the dog-rocker may be coiled about the shaft 72. The connection between the latter and the ribbon-vibrator consists of an arm 84 mounted upon shaft 72; a pull-link 85 connected to said arm and extending forwardly, and an arm 86 connected to said link and mounted upon the vibrator shaft 66. By this means, whenever the dog-rocker is vibrated by the keys, the vibrator is elevated to cause the ribbon to cover the printing point; and upon the return of the carriage-feeding mechanism to normal position, said vibrator drops to permit the ribbon to uncover the printing point.

The carriage may be propelled by a spring-barrel 87 (Figs. 2 and 3), mounted upon an arm 88, projecting laterally and downwardly from the side-bar 44 of the hinged carriage-supporting frame; and a strap 88^a may connect the spring-barrel to the carriage. By mounting both the spring barrel and the carriage-feeding mechanism upon the hinged frame, the latter is permitted to swing freely up and down, without liability of deranging the carriage-controlling devices, which always maintain their proper relation to the carriage, although by reason of the arm 75 swinging away from the finger 76, the latter cannot of course operate the feeding mechanism when the carriage is tilted up.

The ribbon-feeding pawls 54 and 55 may be pivoted at their rear ends upon arms 89 so upstanding from the universal-bar rocker 78, and provided with draw-springs 90 connected at their lower ends to the pawls and at their upper ends to the arm 89, whereby the pawls may be held in engagement with the ratchet wheels 56; each pawl being provided with a stop 91, to prevent undue upward movement thereof when the ratchet wheels are swung away from the pawls at the tilting up of the carriage. Behind the pawls is mounted in the side walls of the machine a horizontal shaft 92, having an operating handle 93, and carrying wings 94, 95, the latter being shown as lifting an arm 96 projecting rearwardly from the pawl 55, so as to hold the toothed end of the latter down out of engagement with its ratchet wheel. The shaft may be rocked to depress the wing 95 and allow said pawl to re-engage the ratchet-wheel, while the other wing 94 rises and lifts an arm 97 provided upon the other pawl, and throws the latter out of engagement, whereby the feed of the ribbon is reversed. Any other suitable ribbon-feeding and reversing ribbon may be employed, and the ribbon spools may be otherwise disposed within the limits of my invention. Preferably advantage is also taken of the hinging of the carriage-support, to enable the latter to be shifted up and down to enable different types to print. Normally the carriage and platen are in an elevated position, as seen in full lines at Fig. 1, thereby enabling the lower-case types 9 to print; while by depressing the carriage and platen (the latter in its depressed position being indicated by a dotted circle at Fig. 1), the upper-case types 10 are enabled to print. The downward movement of the carriage is limited by a pair of adjustable 130

stops 98, and its upward movement by a pair of stops having the form of hooks 99 which overhang lugs 100 projecting forwardly from the carriage-supporting rail 23 at the ends thereof. A spring 101, Fig. 1, sustains the carriage and hinged frame normally against the hooks 99; said spring being caught at its upper end over a pin 102 projecting from the side wall of the machine, and at its lower end being caught in a lever 103, which is fulcrumed at its rear end upon a shoulder-screw 104, and is provided between its ends with a vertical thrust-rod 105, which is guided at its upper end in an eye 105^a formed in the depressed portion 3 of the top plate, and contacts with a boss 107 formed upon the under side of the side arm 44 of the hinged frame, thereby supporting the latter. A stop-pin 108', overlying the lever 103, prevents undue upward movement of the latter when the carriage is tilted up. The lever 103 is provided with a key 104^a, by pressure upon which the pull of the spring 101 may be overcome, and the lever 103 and rod 105 carried down, permitting the carriage and hinged frame to drop and rest upon the screw-stops 98.

The hooks 99, which extend through eyes 105^a in the top plate 3, are fixed upon a rock-shaft 106, whereby they may be vibrated forwardly to release the hinged frame and carriage, to permit the latter to be tilted up; said rock-shaft being provided with a returning spring 107, and being mounted in eccentric-nuts 108, by the adjustment of which the hooks 99 may be elevated or lowered so as to position the platen with accuracy. It will be noted that the hinge 46 of the carriage-supporting frame is in rear of and below the platen, so that the latter may shift downwardly and forwardly in a direction agreeing substantially with the tip of the type-bar segment 6, the forward movement being in this instance, however, very slight.

At Fig. 3 it will be noted that the ribbon comes up in direct paths from the spools to the front side of the platen, and that the ribbon-guiding arms 60, 61 are widely separated, so as to expose to view somewhat more than one of the major divisions upon the platen scale, so that at least one of the whole numbers marked upon the platen scale is always visible to the operator between said arms, and he can readily determine at what point the carriage is standing, an index 109 being preferably formed upon the cross-bar 64 for this purpose. The type-guide has a type-opening 110 above the platen scale, and arms 111 and 112 extending laterally and downwardly from said opening, in a manner to leave exposed all of the platen scale which is visible between the ribbon-guiding arms 60 and 61; said type-guiding arms being connected at their bases

by a bar 113, and the type-guiding frame being secured upon the depressed portion of the top-plate 3 by arms 114 and screws 115. At Fig. 1 it will be seen that the type-guiding frame is tipped rearwardly and substantially parallel with the plane of the type-bar pivots.

Wide variations in the construction and operation of the different mechanisms may be resorted to within the scope of my invention; and portions of the improvements may be used without others.

I do not claim to be the first inventor of an up-and-down shifting platen. Certain of my improvements, however, are applicable where the platen shifts up and down, the exact direction of such movement being immaterial. In using the term "vertically" in such claims as cover said improvements, I intend to include all movements in an up-and-down direction.

Having thus described my invention, I claim:

1. In a typewriter, the combination of a platen carriage adjustable or shiftable bodily into and out of coöperative relation to the type bars, a carriage-tension mechanism for actuating said platen carriage, said carriage-tension mechanism shiftable with said carriage, and an escapement-mechanism for said carriage, said escapement mechanism comprising separable members, one thereof adapted to be actuated normally by the typewriter keys, and the other thereof shiftable with the platen carriage, said last mentioned means operating to hold the platen carriage against movement under the action of the carriage-tension-device when said carriage is shifted or adjusted to a non-working position.

2. In a front-strike typewriter, a carriage-bed, a traveling carriage thereon, said carriage and bed being movable to bring the carriage into coöperative relation with the type bars, escapement mechanism having key-actuated means to maintain a coöperative relation to said platen carriage, and a carriage-driving spring also mounted on said bed to move therewith.

3. In a front-strike typewriter, a carriage-bed, a traveling carriage thereon, said carriage having a feed-rack, and movable into and out of working position, an escapement member on the carriage-bed, a rocking tappet coöperating with said member, the latter moving with the carriage-bed into and out of position to coöperate with the tappet, key-actuated means for operating said tappet, and a carriage-driving spring also mounted on said bed to move therewith.

4. In a front-strike typewriter, a platen-carriage having a rack, a racking frame, a dog-carrier on said racking frame, a tappet in coöperative relation with the dog-carrier, means for adjusting the platen carriage and

the rocking frame up and down, key-levers, a universal bar actuated thereby, bell-crank connections between the universal bar and the tappet, and a carriage-driving spring movable with said rocking frame.

5. In a front-strike typewriter, a platen-carriage having a rack, a rocking frame, a dog-carrier on said rocking frame, a tappet in coöperative relation with the dog-carrier, key-levers, a spacing key and lever, a universal bar coöperating with the key-levers and spacing-lever, a carriage-driving spring, the rocking-frame being liftable together with the platen-carriage and driving spring, and means between the universal bar and the rocking frame for actuating the tappet at different points in the elevation of the platen carriage.

6. In a typewriter, the combination with key-levers and type-bars operated by said key-levers, of a platen, a carriage, said platen normally in the path of said type-bars and movable bodily with said carriage out of said path, propelling mechanism for moving the platen in a direction lengthwise thereof and bodily movable with the platen, and escapement mechanism coöperating with the platen and the key-levers when the latter are moved to operate the platen for letter spacing.

7. In a typewriter, key-levers, type-bars operated by said levers, a platen, a carriage, said platen normally in the path of said type-bars and bodily movable with said carriage out of said path, propelling mechanism for moving the carriage in one direction and bodily movable therewith, and escapement mechanism also bodily movable with the carriage and coöperating with the key-levers and operating to feed the carriage only when the latter is in its normal position.

8. In a typewriter, the combination with a support, of a carriage mounted on said support, a carriage bed arranged on the support along which the carriage is adapted to travel and movable bodily out of said position, key-levers, a rack-bar movable with the carriage, an escapement mechanism having a spring-actuated drum tending normally to force the carriage in one direction and movable with the carriage bed, an arm pivotally held to the carriage bed, a spring normally forcing the arm in one direction, pawls carried by the arm so as to be moved transversely of the rack-bar, and means for operating the arm to permit the carriage to have a step-by-step movement.

9. In a typewriter, the combination with a support, of a carriage normally in position to coöperate with the type bars, a carriage bed arranged on the support along which the carriage is adapted to travel and movable bodily out of said position, a rack-bar movable with the carriage, an escapement mechanism having spring-actuated means

tending normally to force the carriage in one direction, an arm pivotally held to the carriage bed, means carried by the arm so as to be moved transversely of the rack-bar, and means independent of and separable from the arm for operating the arm only when in a normal position to permit the carriage to have a step-by-step movement.

10. In a typewriter, the combination with a shifttable carriage bed, of a carriage normally in position to coöperate with the type-bars, said carriage movable along the bed, said carriage and bed both bodily movable out of said position, a rack-bar movable with the carriage and provided with teeth on the under surface thereof, means normally forcing the carriage in one direction, an arm pivotally held to the carriage bed, means carried by the arm and adapted to engage the rack-bar to permit a step-by-step movement to be given to said carriage, key-levers, and means separable from the said arm when the carriage bed is shifted and operatively connected to the key-levers to operate said arm when the carriage bed is in its normal position only.

11. In a typewriter, the combination with key-levers and type-bars operated thereby, of a platen, a carriage, said platen being normally in the path of the type-bars, and movable bodily with the carriage out of said path, propelling mechanism for moving the platen in a direction lengthwise thereof and bodily movable with the platen, and escapement mechanism coöperating with the platen and key-levers when the latter are moved to operate the platen for letter-spacing.

12. In a typewriter, the combination with a support, of a carriage normally in position to coöperate with the type-bars, a carriage-bed arranged on the support along which the carriage is adapted to travel and movable bodily out of position to coöperate with the type-bars, a rack-bar movable with the carriage, escapement devices, spring-actuated means on said bed tending normally to force the carriage in one direction, an arm pivotally held to the carriage-bed, means carried by the arm so as to move transversely of the rack-bar, and means independent of and separable from the arm for operating the arm only when in a normal position to permit the carriage to have a step-by-step movement.

13. In a typewriter, the combination of a platen-carriage and platen bodily movable into and out of coöperative relation to the type-bars, a tension-mechanism for said carriage, and an escapement-mechanism for said carriage, said escapement-mechanism comprising means upon the framework of the machine to be operated by the typewriter-keys, and also comprising means to hold the platen-carriage against movement
